UNITED STATES PATENT OFFICE.

FRANK C. HOBBS, OF MUSKEGON, MICHIGAN, ASSIGNOR TO BRUNSWICK-BALKE-COLLENDER CO., A CORPORATION OF DELAWARE.

DISCHARGEABLE BOTTOM FOR THE POCKETS OF POCKET-BILLIARD TABLES AND THE LIKE.

1,116,890.

Specification of Letters Patent.

Patented Nov. 10, 1914.

Application filed May 18, 1914. Serial No. 839,357.

To all whom it may concern:

Be it known that I, FRANK C. HOBBS, a citizen of the United States, and a resident of the city of Muskegon, in the county of Muskegon and State of Michigan, have invented certain new and useful Improvements in Dischargeable Bottoms for the Pockets of Pocket-Billiard Tables; and I do hereby declare that the following description of my said invention, taken in connection with the accompanying sheet of drawings, forms a full, clear, and exact specification, which will enable others skilled in the art to which it appertains to make and use the same.

This invention relates generally to improvements in a dischargeable bottom for the pockets of pocket billiard tables, and it consists, essentially, in the novel and peculiar combination of parts and details of construction, as hereinafter first fully set forth and described and then pointed out in the claims.

In the drawings already referred to, which serve to illustrate my said invention more fully, Figure 1 is an elevation of a fragment 25 of a pocket billiard table, showing the dischargeable bottom as applied to a corner pocket. Fig. 2 is a vertical section in line 2—2 of Fig. 1. Fig. 3 is a horizontal section in line 3—3 of Fig. 2. Fig. 4 is a section of a detail of construction at line 4—4 of Fig. 3. Fig. 5 is a vertical section of another detail.

Like parts are indicated by corresponding symbols and characters of reference in all 35 the figures of the drawing.

The object of this invention is the production of an easily actuated, simple, neat, and efficient dischargeable bottom applicable to the ball pockets of pocket billiard tables, 40 whereby easy removal of billiard balls dropped into said pockets is accomplished.

To better understand my invention, I now refer to the drawings, in which—

A indicates a fragment of a typical pocket 45 billiard table.

B is the billiard cloth; C, the slate bed; D, the slate frame; E, the head block; F, the cushion rails; G, the cushions; H, the pocket irons, and I, the pockets proper, which latter 50 may be of any preferred form or construction, so long as the lower end thereof is provided with a circular outlet 1 slightly greater than the diameter of a billiard ball.

To the lower end of pocket I is affixed my

improved dischargeable bottom M, which 55 comprises a cylindrical, preferably sheet metallic shell 2 having an inturned and down turned edge 2^a at its upper end whereinto the lower end of pocket I is adapted to be made fast. Said shell 2 has around its periphery a plurality of longitudinal slots 3, through which is laced a fabric or leather band 4 as clearly indicated in Fig. 3. The purpose of this band is first to remove the billiard balls from intimate contact with the 60 metallic shell and second to afford a certain amount of ornamentation.

At one side of shell 2, at the lower edge thereof, there is a semi-circular cut out 4^a of a diameter slightly larger than that of a billiard ball. The margin of cut out 4^a is provided with an in and upturned edge 5 into which is "crimped" a protecting strip of fabric or leather 6, which latter prevents contact of the billiard balls with the otherwise sharp margin of the cut out.

The lower end of shell 2 is possessed for half its circumference of an inturned flange 7 to provide a rest for an annular member 8 which is pivoted within the shell 2 at a point forwardly of the medial point or line thereof, as at 9, whereby there will be an overbalance of weight tending to maintain said annular member against said seat or rest 7. Depending from the rear of annular member 8 is a finger 10, which is capable of receiving a counterweight 11 so as to create an additional tendency to maintain the annular member against the rest 7. The object of finger 10 is to provide means 90 against which the fingers of a hand may be pressed in order to tilt member 8 about its pivot 9 as shown in dotted lines in Fig. 2 to permit the egress, by the force of gravity, of billiard balls within the pocket I.

Annular member 8 may be formed from sheet metal with an inverted U-shaped cross section. A plurality of prongs 12, Figs. 3 and 4, are pierced from and bent up at right angles to the top face of said member, and are adapted to be pressed into and clenched within a leather washer 13, which is provided as a cushion for the billiard balls 100 dropped into pocket I.

To provide for attachment of the shell 2 to any class or type of pocket other than shown in the drawing, I may apply to the in and down turned edge 2^a of the shell 2

a strip of leather or like material 14 of suitable width, which in turn may be fixed to the selected pocket, or even attached directly to the pocket irons H if desired.

5 While herein I have disclosed the preferred mode of practising my invention, I may make such changes and alterations therein as might suggest themselves to the skilled mechanic and permitted under the 10 doctrine of equivalents.

Having thus fully described my invention I claim as new and desire to secure to myself by Letters Patent of the United States:—

15 1. A dischargeable bottom comprising a cylindrical shell having one side cut out at its lower end, the opposite side of said shell having an inturned lower flange, and an annular member pivoted in the lower end 20 of said shell, away from the medial line thereof, a portion of said member being adapted to rest upon said flange.

2. A dischargeable bottom adapted for the reception of billiard balls and the like 25 comprising a cylindrical shell having one side cut out at its lower end, said cutout being of smaller size than the contents of said shell, the opposite side of said shell having an inturned lower flange, and an 30 annular member pivoted in the lower end of said shell away from the medial line thereof, a portion of said member being adapted to rest upon said flange.

3. A dischargeable bottom adapted for 35 the reception of billiard balls and the like, comprising a cylindrical shell having one side cut out at its lower end, said cutout being of smaller size than the contents of said shell, the margin of said cutout being 40 faced with a yieldable fabric, and an annular member pivoted in the lower end of said shell away from the medial point thereof, there being a depending finger on said member, and means limiting the downward 45 movement of said member adjacent said finger.

4. A dischargeable bottom comprising a cylindrical shell having one side cut out at its lower end, the margin of said cut out being 50 faced with a yieldable fabric, the opposite side of said shell having an inturned lower flange, and an annular member piv-

oted in the lower end of said shell, there being a depending finger on said member.

5. A dischargeable bottom comprising a 55 cylindrical shell having one side cut out at its lower end, the margin of said cut out being faced with a yieldable fabric, the opposite side of said shell having an in-turned lower flange, and an annular mem- 60 ber pivoted in the lower end of said shell away from the medial line thereof, there being a depending finger on said member.

6. In combination, a cylindrical shell 65 adapted for the reception of billiard balls and the like, there being a cutout in the side wall thereof at its lower end, of smaller size than said billiard balls, an annular member pivoted within said shell at said lower end away from its medial line thereof in a direction toward said cutout, and means at the lower end of the wall opposite said cutout, preventing the downward movement of the adjacent portion of said member.

7. In combination, an open ended shell 75 adapted for the reception of billiard balls and the like, there being a cut out in the side wall thereof at its lower end, a member pivoted within said shell, normally closing the lower end thereof, and means at the lower 80 end of the wall away from said cut out, preventing the downward movement of the adjacent portion of said member when the same is in normal position.

8. In combination, an open ended shell 85 adapted for the reception of billiard balls and the like, there being a cut out in the side wall thereof at its lower end, a member piv- 90 ceted within said shell away from its medial line thereof in a direction toward said cut out, normally closing the lower end thereof, and means at the lower end of the wall away from said cut out, preventing the downward movement of the adjacent portion of said member when the same is in normal posi- 95 tion.

In testimony whereof I have hereunto set my hand in the presence of two subscribing witnesses.

FRANK C. HOBBS.

In the presence of—

J. O. MATTESEN,
J. O. MILLER.
